UNITED STATES PATENT OFFICE.

IRA T. SWARTZ, OF INDIANAPOLIS, INDIANA, ASSIGNOR TO SWARTZ ELECTRIC CO., OF INDIANAPOLIS, INDIANA, A CORPORATION.

DESIGN FOR A PEDESTAL FOR ELECTRIC SWITCHBOARDS.

46,811.

Specification for Design.

Patented Dec. 29, 1914.

Application filed July 27, 1914. Serial No. 853,495. Term of patent 14 years.

To all whom it may concern:

Be it known that I, IRA T. SWARTZ, a citizen of the United States of America, residing in the city of Indianapolis, in the county of Marion and State of Indiana, have invented a new and original and ornamental Design for a Pedestal for Electric Switchboards, of which the following is a specification, reference being had to the accompanying drawing, forming a part hereof.

Figure 1 shows a front elevation of my

pedestal with a switch board in dotted lines. Fig. 2 is a side elevation of the same. Fig. 3 is a plan view of the same.

I claim:

The ornamental design for a pedestal for electric switch boards shown.

IRA T. SWARTZ.
